UNITED STATES PATENT OFFICE.

IRVING W. MASON, OF ABERDEEN, WASHINGTON.

POISON-INDICATOR.

1,241,536.

Specification of Letters Patent.

Patented Oct. 2, 1917.

Application filed April 24, 1917. Serial No. 164,219.

To all whom it may concern:

Be it known that I, IRVING W. MASON, a citizen of the United States, residing at Aberdeen, in the county of Grays Harbor and State of Washington, have invented a new and useful Poison-Indicator, of which the following is a specification.

The subject of this invention is an indicator adapted for attachment to a bottle containing poison or other injurious matter.

The primary object of this invention is to provide means normally locked on the neck of a bottle for indicating the nature of its contents.

Another object is to prevent young children from drinking from the bottle.

Another object is to construct the indicator from a metallic blank capable of being struck into a desired form by one operation of a machine.

A further object is to provide means for preventing displacement of the indicator while dispensing the contents of the bottle.

Still another object is to provide an indicator with means for preventing the liquid from coming in contact with the indicator when being poured from the bottle.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings:

Figure 1 is a plan view of the invention; Fig. 2 is a sectional view on the line 2-2 of Fig. 1;

Fig. 3 is a side elevation of the indicator showing it applied to the neck of a bottle.

Fig. 4 is a plan view of the metallic blank used in constructing the indicator, showing the same as it appears after being stamped or cut out and before bending the parts into place.

Referring to the drawings by numerals:

The indicator consists of an annular body 1 adapted to be seated on the head of a bottle 2, and surround the mouth thereof. Depending fingers 3 are formed on the outer

periphery of the body 1 and each finger is 55 formed adjacent its end with an inwardly curved portion 4 which is adapted to grip the neck of the bottle immediately below the annular bead or rim 5. An outwardly flared end 6 terminates each finger and serves to 60 guide the finger over the bead 5, when the indicator is being placed on a bottle.

One sector 7 of the body 1 is bent, as shown most clearly in Fig. 3, to form an arch extending upwardly from the head of 65 the bottle, and through this arch the contents of the bottle may be poured without contacting the metal of which the indicator is formed.

Upwardly and outwardly curved tines or 70 prongs 8 rise from the inner periphery of the body 1, along that portion not included within the arch 7. Each tine is provided with a sharp point 9 which will come in contact with the finger of one attempting to 75 withdraw the cork in the dark or without looking. The tines are so placed, however, that the cork may be easily withdrawn by one giving that operation his attention.

As is indicated by Fig. 4, these indicators 80 may be cut from sheet metal by the ordinary stamping or die process, and the cutting and bending into form may all be performed at the one operation.

Having described my invention, what I 85 claim as new and desire to secure by Letters Patent, is:

1. A poison indicator, comprising a body portion, an arch formed in the body portion to permit a flow of liquid therethrough, 90 means integral with said body portion for holding the indicator upon the neck of a bottle, and means formed on the body portion for indicating the nature of its contents.

2. A poison indicator comprising an annular body portion, an arch formed in the body portion, gripping fingers spaced about the outer periphery of the body portion, and prongs struck up from the material at the center of the body portion.

In testimony that I claim the foregoing as my own, I have hereto affixed my signature in the presence of two witnesses.

IRVING W. MASON.

Witnesses:

CHESTER R. JONES,
FRANK J. KLOOSTER.
